CONCRETE TUNNEL LINING

Carl T. Forsberg, New York, N. Y.

Application May 18, 1936, Serial No. 80,242

13 Claims. (Cl. 61—45)

This invention relates to improvements in tunnel linings and more particularly to means for and method of placing concrete linings within the metallic hollow cylindrical casing of subaqueous and other tunnels.

It is an object of the present invention to prevent the formation of hollow spaces within the concrete linings of tunnels.

It is another object of the invention to provide means for completely filling each segment of the metallic tunnel lining completely with concrete during the process of placing the same.

It is a further object of the invention to eliminate the necessity of drilling through the hardened concrete lining into empty spaces of the concrete lining and to fill them by pressing grout into them.

It is a further object to provide a stronger and more uniform concrete lining in a single operation than has heretofore been possible by the refilling method.

It is another object to reduce the labor required for forming concrete linings and thereby to accelerate the time required for building a tunnel.

It is a further object to make it possible to produce a stronger concrete lining by producing monolithic concrete (concrete in one piece) rather than concrete in more than one piece by the refilling method.

With these and other objects in view the invention consists in a novel method of procedure in preparing the metallic outer tunnel lining for placing of the interior concrete lining and in novel means and arrangements to be applied for this purpose which will become clearer as the description progresses in connection with the appended drawings in which—

Fig. 1 is a vertical section through a tunnel provided with an exterior metallic lining embodying the present invention.

Fig. 2 shows a quadrant vertical section transverse of a metallic tunnel lining embodying the present invention.

Fig. 3 is a longitudinal section of the tunnel linings on line 3—3 of Fig. 2.

Fig. 4 is an interior view longitudinally of the tunnel on line 4—4 of Fig. 1 showing only the metallic lining.

Fig. 5 is a vertical transverse quadrant section through the metallic lining of a tunnel as shown in Fig. 2 prepared for placing concrete in accordance with the present invention.

Fig. 6 is an enlarged detail section showing a joint of two cast metal sections of a tunnel lining embodying the present improvements and prepared for placing the inner concrete lining in accordance with the improved method.

Fig. 7 shows a section similar to that of Fig. 6 through a sheet steel tunnel lining also prepared

for placing the interior concrete lining in accordance with the improved method.

Fig. 8 shows a modified form of the invention for use on a cast metal tunnel lining.

Fig. 9 is a sectional view on line 9—9 of Fig. 8. 5

Fig. 10 is a detail of a cross arm for holding the air tubes on the segment flanges.

Fig. 11 is a detail of a tubular rivet for joining the tunnel segments.

In the construction of subaqueous and other 10 tunnels cast iron or steel rings consisting of segments 15 which are bolted together by means of flanges 16 and 17 thereon are generally used to form a cylindrical lining within the blasted or otherwise excavated tubes. The segments forming one ring are preferably offset or staggered 15 against those of the two adjacent rings so that the horizontal flanges 17 form broken lines longitudinally of the tunnel.

When a plurality of lining rings have been assembled and bolted together circumferentially by bolts 19 and longitudinally by bolts 19a, the hollow portions of all segments 15 are filled with concrete to a point beyond the flanges 16 and 17 so as to form a solid concrete cylinder 14 of several inches thickness inside of said flanges. For 20 this purpose a form preferably of sheet metal plates curved to fit the inner radius of the concrete lining to be formed is supported by false-work and spaced the desired distance from the 25 inner faces or edges of flanges 16 and 17 within the rings to be concreted.

At first a form-segment is placed above the bottom segments of the rings as viewed in Fig. 5, and the spaces between this form and the metal webs of the segments 15 are filled with plastic concrete. When this concrete has set the forms are moved circularly upward opposite the tunnel rings to cover with the same spacing the next higher segments and concrete is again poured between 30 the forms and webs of the tunnel segments and this process is continued until all segments of the metallic tunnel lining are covered by a hollow concrete cylinder of approximately uniform thickness of several inches inside of flanges 16 35 and 17.

While this method is satisfactory for the lower half of the tunnel lining it is not so for the upper half of the lining, as in pouring the concrete the flanges 17 prevent the complete filling of the segments above the central horizontal plane of the tunnel and at the places indicated at 18 air is trapped in each segment forming hollow spaces in the segments 15 which spaces increase in size 40 towards the top of the lining as shown in Fig. 2. 45 Of course by pushing and tamping, these spaces can be partly filled with concrete but not entirely. It has therefore become the practice to drill a pair of holes into these hollow spaces when the concrete has set and press cement grout into 50 55 60

them through one hole, while the air escapes through the second hole, obviously a tedious and costly process. It is an object of this invention to prevent the forming of these air pockets by a simpler and less expensive method.

The present invention contemplates providing novel mechanical means for preventing the formation of air pockets at the joints when pouring concrete.

10 Fig. 5 shows the metallic segments in the upper half of a tunnel ring bolted together by bolts 19 and a steel plate form 20 in its place for pouring the concrete lining between the segments 15 and said form 20. Each bolt 19 carries a sheet metal plate 21 shaped as shown in Fig. 10 and provided at its upper end with a washer-like eye, from which a central stem 21a extends. Stem 21a is provided with a plurality of spaced cross arms 21b. The eye portion 21 of the plate is placed over the head of a bolt 19 or under its nut and stem 21a is bent around the abutting flanges of the two segments 15 joined together by said bolt. The cross arms 21b are bent around a tubular member 22 which is curved around the same flanges extending from the highest point in the lower segment 15 to approximately the middle of the next higher segment 15. The cross arms 21b hold the member 22 securely connected to flanges 17. Each cross arm 21b is preferably provided with an aperture 21c through which a tie wire 25 may be passed when necessary to tie up the long arm of tube 22 and hold it in desired position.

It will be seen by comparing Figs. 2 and 5 that the lower openings of tubes 22 are located in the segments at the highest points of the spaces 18 where air is trapped as shown in Fig. 2. When concrete is poured into these segments the otherwise trapped air escapes through tube 22 into the next higher segment and exhausts at a place higher than the top of the concrete in the lower segment. The pouring of concrete may proceed uninterruptedly because from each higher segment the air escapes in the same manner, so that the plastic concrete will completely fill them when pressed in except the highest segment in which two tubes 22 will discharge air from the next two lower segments. A third straight vertical tube 23 is mounted in the top segment to reach to the highest point in that segment. Tube 23 is preferably passed through an aperture of form 20, and preferably consists of two parts joined by a union 23a so that the lower part may be removed when the concrete has set and the opening be plastered over. The tubes 23 are preferably provided at their upper ends with a wire hook 23b welded to the outside of the tube. This hook is placed into an aperture formed in the wall of tubes 22 near their upper or lower end to prevent vertical motion as illustrated in Fig. 5. Hook 23b permits the lower end of tube 23 to move when the aperture in the form 20 is out of vertical alignment with the top of the tube which must remain in fixed place. It is evident that by means of tube 23 the uppermost segments of the tunnel rings are also relieved of all air that could be trapped therein and that they, like all other segments, will be completely and solidly filled with concrete. When the rings of the metallic tunnel lining are filled consecutively in longitudinal direction of the tunnel the tubular members 22 can be attached to the bolts in the circular flanges 16 of the metallic lining and bent around these flanges to discharge the air from

the highest space in each segment to be filled into the adjacent forward tunnel segment which will be filled later as shown in Fig. 3 with the same beneficial result. The tubes 23 alone may be used to remove the trapped air from the high spaces 5 of any segment by mounting them radially by means of cross arms 21 or other suitable means so that their upper end reaches into the high space where air will be trapped and their lower end extends through the form plate 20 as shown 10 in Fig. 5.

In Fig. 8 a modified tubular means for removing trapped air from the segments 15 is illustrated. It shows that one of the bolts 19 is omitted and in its place a tubular rivet 24 is used. 15 It will be seen from Figs. 5 and 6 that the bolts 19 do not quite fill their apertures but leave a hollow annular space between bolt and flange metal. The tubular rivet 24 fits the aperture closely and the thickness of its wall can easily be 20 so proportioned that its cross-sectional area is equal to that of the bolt at the root of its thread and therefore equals the tensile and shearing strength of the solid bolt. When the tubular rivet has been placed into its aperture the cylindrical end is upset into the countersunk opening of the bolt hole and the flanges 17 or 16 are as securely riveted together as they can be bolted. A short tube 25 provided with a curved end portion is then tightly driven into the hollow of the 30 tubular rivet 24 so that the opening of the curved portion comes into the highest part of the lower segment where air may be trapped. A straight tube 26 of smaller diameter is then tightly driven from the side of the higher segment 15 into the 35 hollow part of the rivet or tube 25 to complete an air passage from the top space of a lower tunnel segment into the free air space of the next higher one.

In practice more than one, or all bolts joining 40 two segments may be replaced by these tubular rivets without impairing the strength of the joints and the circuitous path around the segment flanges may be eliminated in a neat and inexpensive way.

45 The air tubes 22, 25 and 26 remain in the solid concrete and serve as reinforcing rods of the joints between the segments in circular and longitudinal directions. Those parts of tubes 25 and 26 which are within the tubular rivets 24 are preferably slightly tapered to provide a stronger joint and the openings in the free ends of tubes 25 are flattened to reach as close as possible into the corner of segment 15. These open ends of the tubes 22 and 25 are preferably covered with a 55 cap of wire mesh 27 or other suitable means to prevent stones or small pebbles of the concrete aggregate to obstruct the air opening.

50 By the above described method and means it is possible to build a monolithic tunnel lining in one 60 continuous operation and to eliminate the work of drilling into air spaces and of filling them with grout. In addition thereto the lining produced by this process and the means described furnishes a stronger lining by means of the additional tubular steel reinforcing which joins the segments to each other in addition to the bolts which hold the segments together.

65 It will be understood that modifications may be 70 made in the details of execution of the aforescribed process without departing from the principle of the invention and it is desired to be limited only by the prior art and the appended claims.

I claim:

1. The herein described method of constructing tunnel linings which consists in permanently placing an arcuate shaped form having inwardly extending peripheral flanges in the excavated tunnel, mounting another form of similar shape on the first named form so that their flanges abut, bolting the flanges, placing a tubular member with one opened end in the lower form adjacent to its flange and with its other opened end in the upper form at a point remote from its flange, mounting a temporary arcuate shaped form adjacent the inner edges of the flanges, pouring plastic concrete into said forms and permitting said concrete to harden and lastly removing said temporary form.
2. The method of preventing the formation of air bubbles in a concrete tubular tunnel lining consisting in placing a tubular member between the sectional joints of the forming member, with one end of the tubular member in one section adjacent the joint and with the other end of the tubular member in the other section remote from the joint.
3. In a tunnel lining having arcuate shaped segments and inwardly extending and abutting flanges, a tubular member having one of its open ends bent around the flanges and terminating adjacent the innermost end of the flange in one segment and having its other end terminating in the adjacent segment at a point remote from its flange for exhausting air from the first named segment.
4. A segment of a tunnel lining comprising an arcuate section of metal lining having inwardly extending and abutting flanges, means for securing the flanges together, a bracket depending from said fastening means and a tubular member supported by said bracket, said tubular member having one of its open ends positioned on one side of the abutting flanges and its other open end on the other side of the flanges, for exhausting air from the first named side of the flanges.
5. A tunnel lining comprising a plurality of arcuate shaped sections having abutting flanges, means for fastening the flanges together, the sections above the horizontal plane of the tunnel being provided with means for exhausting the air therefrom, said means consisting of a tubular member supported by each pair of abutting flanges, with one of its open ends in one section adjacent the innermost end of the flange of said section and with its other open end in the other section remote from its flange.
6. A tunnel lining comprising a plurality of arcuate shaped sections having abutting flanges, a bolt passing through said flanges for fastening the same, a bracket fastened to the bolt, integral arms on said bracket, and a tubular member supported by said arms, said tubular member having one open end bent around the abutting flanges and terminating at a point adjacent the inner end of the flange of one section and its other open end positioned in the adjacent section remote from its flange.
7. Tunnel lining construction comprising a plurality of superimposed arcuate shaped segments with inwardly extending abutting flanges, bolts passing through the abutting flanges for fastening the same and a device positioned between the joints of the respective abutting segments above the horizontal axial plane of the tunnel for exhausting the air therefrom when concrete is
